HOOD CATCH

Raymond G. Moore, Bridgeport, Conn., assignor
to The Bassick Company, Bridgeport, Conn.,
a corporation of Connecticut

Application February 10, 1932, Serial No. 591,951

3 Claims. (Cl. 292—48)

The present invention relates to improvements in hood catches, particularly of the type having catch means interiorly and at each end of the hood, and which are adapted to be operated by a single exteriorly arranged operating handle disposed substantially centrally of the hood. In one type of catch heretofore in use a torsional rock shaft was provided extending substantially the length of the hood and had a series of crank means for rotating the shaft and for engaging keeper brackets. This type of catch depended on the spring tension produced by torsional twisting of the shaft, and because of its length and the constant twisting to which it was submitted was subjected to mal-adjustment, rapid deterioration, vibration, and other objectionable conditions. It is proposed in the exemplary illustrated embodiment of the present invention to provide catch means at each end of the hood, in the form of independently formed crank members, operating handle means, which may be placed at any desired point vertically of the hood, and movement translating means between the handle means and catch means including a vertically movable member having spring arms connected to the catch means, and which are adapted to be tensioned by bending lengthwise as the catch means are moved into operative position.

Another object is to provide a hood catch which will adapt itself to variations in the longitudinal and vertical dimensions of the hood without material change in the catch structure. A further object is to provide a hood catch which will insure positive and proper engagement of the catch means at each end of the hood, irrespective of variations and irregularities that may occur in the disposition of the hood and the arrangement of the keeper means. A still further object is to provide a hood catch which will effectually hold the hood downwardly and inwardly.

With the above and other objects in view an embodiment of the invention is shown in the accompanying drawing, and this embodiment will be hereinafter more fully described with reference thereto, and the invention will be finally pointed out in the claims.

In the drawing:—

Fig. 1 is a horizontal sectional view through the hood and frame and showing the catch in plan, the same being in its operative position, intermediate portions of the hood and catch being broken away.

Fig. 2 is an interior elevation showing the operative position of the catch, and indicating the inoperative position by dotted lines.

Fig. 3 is a vertical sectional view, taken along the line 3—3 of Fig. 2.

Similar reference characters indicate corresponding parts throughout the several figures of the drawing.

Referring to the drawing, the automobile hood 10 is adapted to close in the usual manner against the lacings 11 and 12 of the radiator frame 13 and cowl portion 14 of the chassis.

Upon the inner face of the hood, and preferably at a central point between the hood ends and near the upper edge of the hood side, there is riveted or otherwise suitably secured a bracket plate 15 having a pressed up circular bearing boss 16 provided with a central aperture 17 in alignment with an aperture 18 in the hood. A shouldered cylindrical bearing bushing 19 is secured within the aperture 17 by swaging over, as at 20, and projects into the aperture 17 in the hood, so that it is slightly outside of the hood surface to form a suitable bearing for the rotatable operating handle, presently to be described. The boss is preferably dished, as at 21, in surrounding relation to the aperture 17.

The handle 22 is provided with a reduced diameter shank 23 which is journaled in the bushing 19, and at its inner end is provided with a threaded hole 24 and wedge shaped lugs 25—25 at each side thereof and upon which a crank arm 26 is engaged, the crank arm being provided for this purpose with a beveled edge rectangular opening 27, which engages the lugs with a tight wedge fit. A headed screw 28 is screwed into the threaded hole 24 and secures the crank arm in tight non-rotatable relation to the handle shaft 23, and at the same time retains the handle in its bearing.

The crank arm 26 is provided at one end with an inwardly projecting crank pin 29 engaged with a slot 30 of a slide member 31, mounted for vertical movement in vertical slots 32—32 provided in a pair of flanges 33—33 bent inwardly from the vertical side edges of the bracket plate 15. The slide member 31 is provided with a pair of elongated arms 34 and 35 extending at each side of the bracket plate and to which are secured a pair of spring rods 36 and 37, which in turn are connected to the catch means, to be hereinafter more fully described. The rods are conveniently secured to the slide member by providing enlarged ball-like heads 38 and 39 upon their inner ends, the inner end portions of the rods being disposed in longitudinal cylindrical sockets 40 and 41 formed in the arms 34 and 35 and the ball ends 38 and 39 being disposed in bulged out enlargements 42 and 43 at the inner ends of said sockets. The slide member is preferably formed of sheet metal folded upon itself along its lower edge, so that the rod ends may thus be conveniently enfolded and assembled in the sockets during formation of the slide member.

The intermediate portion of the slide member between the bracket flanges 33—33 is extended upwardly with respect to the upper edge of the extension arms 34 and 35, and the two folded portions are 120

secured together along the upper edge by a flange 44, at the upper edge of one portion folded over and upon the back of the other portion. For convenience in assembling the slots 32-32 of the bracket are provided with clearance cuts 45 and 46 near their lower ends so arranged as to clear the folded over flange 44 and the bulged socket portions 42 and 43 of the slide member, thus permitting the slide member to be longitudinally engaged with the bracket through the slots 32-32. When assembled the enlargement formed by the flange 44 which is wider than the slots 32-32 prevents longitudinal displacement of the slide by abutment with the inner sides of the flanges 33-33.

It will be observed that the slot 30 extends at one side of the center of the slide member, so that rotation of the operating handle and crank 26 between the operative and inoperative positions is limited to an oscillatory movement through 180°. The slot is provided at its inner end with a detent recess 47, in which the crank pin 29 seats under tension in the operative position, and thus yieldably retains the parts in position. This detent portion is preferably centrally of the coupling member, the slot extending at one side of the center, so that in the operative position the pin is centralized between the spring rods 36 and 37 and exerts an even lifting pressure thereon.

The spring rods 36 and 37 are extended into proximity to the end extremities of the hood and are respectively provided with eye-loops 48 and 49, engaged by eye-loops 50 and 51 provided at the upper ends of a pair of connecting rods 52 and 53 provided with eye-loops 54 and 55 at their respective lower ends and which are connected to the catch members 56 and 57 at each end of the hood. These catch members are preferably formed of wire stock bent into substantially rectangular form and are hingedly mounted on the hood by means of brackets 58 and 59 riveted to the hood and curled about one side of the brackets. The swinging ends are respectively provided with bent bearing portions 60 and 61 to which the eye-loops 54 and 55 are connected.

The catch members 56 and 57 are adapted to engage angular keeper brackets 62 and 63, suitably mounted on the radiator frame and cowl, or upon any other convenient part of the chassis in proximity to the hood ends. These brackets are illustrated as formed of sheet metal, and their engaging faces which are preferably disposed at an angle of 45°, are respectively provided with pressed out rounded ribs 64 and 65 for engagement by the rounded crank ends, this arrangement providing positive and firm engagement, irrespective of variations in the mounting and disposition of the parts.

60 The operation is as follows:—

As shown by dotted lines in Figs. 2 and 3 the hood catch is in its inoperative or released position, the catch members 56 and 57 in this case depending so that they clear the keeper brackets 65 as the hood is closed against the lacings, and the spring rods 36 and 37 being in their straight untensioned relation. As the handle 22 and crank arm 26 are turned to the operative position shown in full lines the slide member 31 is moved upwardly in the slots 32, drawing the rods 52 and 53 upwardly. This movement first

brings the swinging ends of the catch members under and into engagement with the keeper brackets, whereupon the spring rods 36 and 37 are sprung under tension as the movement of the handle is completed, thus putting the catch members under tension, so that the hood is effectually held downwardly and inwardly through the tendency of the catch members to move upwardly on the inclined keeper surfaces. In the operative position the crank pin 29 engages the detent recess 47 and the parts are thus yieldably held in operative position under the tension of the spring rods 36 and 37.

I have illustrated and described a preferred and satisfactory embodiment of my invention, but it will be understood that changes may be made therein, within the spirit and scope thereof, as defined in the appended claims.

Having thus described my invention, what I claim and desire to secure by Letters Patent is:—

1. In a hood latching device, movable catch means for engaging keeper means, a movement translating slide member having up and down movement, a flexible tension rod rigidly supported at one end by said slide member, a link connected between its other end and said catch means, and manually operable actuating means for imparting movement to said slide member, whereby said catch means is moved into and out of operative relation with said keeper means, said tension rod adapted to be sprung between its ends under tension in the operative relation of said catch means.

2. In a hood latching device, movable catch means for engaging keeper means, a movement translating slide member differentially movable with respect to said catch means having up and down movement, a flexible tension rod rigidly supported at one end by said slide member and movably connected at its other end to said catch means, and manually operable actuating means for imparting movement to said slide member, whereby said catch means is moved into and out of engagement with said keeper means, and said actuating means adapted to have further movement whereby further movement is imparted to said slide member and said tension rod is sprung between its ends under tension in the full operative relation of said catch means with said keeper means.

3. In a hood latching device, a plurality of movable catch means for engaging spaced keeper means, movement translating means differentially movable with respect to said catch means disposed intermediate said catch means and having up and down movement, flexible tension rods rigidly supported at one end by said slide member and movably connected at their other ends to said respective catch means, and manually operable actuating means for imparting movement to said movement translating means whereby said catch means are moved into and out of engagement with said keeper means, and said actuating means adapted to have further movement whereby further movement is imparted to said slide member and said tension rods are sprung between their ends under tension in the full operative relation of said catch means with said keeper means.

RAYMOND G. MOORE.
